SAFETY MECHANISM FOR CENTRIFUGAL MACHINES

Christian F. Meyer, Wyomissing, Pa., assignor to Textile Machine Works, Wyomissing, Pa., a corporation of Pennsylvania

Application August 19, 1930, Serial No. 476,360

20 Claims. (Cl. 192—136)

This invention relates to safety devices for machines such as centrifugal extractors having a protective guard or cover, and more particularly to safety control and locking means for such a 5 guard the main objects being to provide novel and simple means preventing the opening of the guard while the parts being protected thereby are in operation, and maintaining such operative parts disconnected from the driving means while 10 the guard is unlocked.

The invention comprises the novel elements, features of construction and arrangement of parts in cooperative relationship as herein fully disclosed by the following detailed description and 15 accompanying drawings of one embodiment thereof, reference to which will make the above as well as other objects and attendant advantages more readily apparent.

Referring to the drawings:—

20 Fig. 1 is an elevational view of a known centrifugal extractor having my invention applied thereto, the casing as well as other parts being broken away and in section.

Fig. 2 is a fragmentary view similar to Fig. 1 but showing certain parts in another position.

25 Fig. 3 is an elevational view of the upper rear end of the machine, as seen by looking in the direction of the arrow A in Fig. 2.

Figs. 4, 5 and 6 are similar fragmentary 30 detail views of the cover hinge and associated parts in various positions; Fig. 4 being taken substantially on the line 4—4 of Fig. 3.

Fig. 7 is a fragmentary sectional view taken substantially on the line 7—7 of Fig. 6.

35 Fig. 8 is a fragmentary central sectional view through the centrifugal clutch device forming part of my invention.

Fig. 9 is a partial bottom plan view of the 40 clutch device shown in Fig. 7, certain parts being broken away and others omitted to more clearly show the details of construction.

Fig. 10 is a fragmentary detail view of certain 45 parts of the clutch device shown in Fig. 8, as seen by looking in the direction of arrows 10—10.

For illustrative purposes, my invention is shown 50 applied to a known centrifugal hydro-extractor of the portable type usable primarily in dye-houses, laundries or homes, for the purpose of extracting water or aqueous solutions from clothing and textile materials during dyeing or laundering. Such a machine is ordinarily provided with a 55 guard or cover which is closed during operation to prevent contact with the rotating container or other moving parts, as well as to prevent material

from accidentally flying out of its container during gyration.

Automatic mechanism is commonly provided in connection with such a machine which prevents the guard from being opened during operation of the machine and also to prevent the machine or its container from being operated while the guard is open or unlocked; and my invention is mainly directed to improved and novel mechanism for accomplishing this, which is simple in construction and more particularly adapted to centrifugal machines of the character mentioned.

To facilitate the understanding of my invention only such known parts of the extractor directly connected and cooperating with the same 70 have been indicated in the drawings.

As shown, the extractor comprises essentially a gyrating unit consisting of a basket or container 12 and a motor 13 for driving the same; the unit being mounted for free movement on 75 suspension rods 14 suitably connected with the unit and rigid frame members or posts 15. The mechanism is enclosed in a casing 16 and the entire structure mounted on wheels 17.

The container 12 and casing 16 are open at their 80 top to permit of ready access to the container, and a protective cover or guard 18 is provided for the purpose mentioned.

In accordance with my invention I provide a 85 separate shaft 19 on which the container 12 is rockably or otherwise secured in known manner, which shaft rotates in a bearing 20 forming part of a housing, in the lower end of which the motor 13 is mounted and to which the suspension rods 14 are loosely connected. The container 90 shaft 19 is in axial alignment with the motor shaft 13a (see Fig. 8) and connected or disconnected with the latter by a centrifugal clutch device generally indicated by the numeral 21.

This device comprises a housing or shell 22 fixedly keyed to the container shaft as shown, and a circular mounting member 24 similarly keyed to the motor shaft 13a. A circular disk 25 is secured to the member 24 by screw bolts 26 on which arcuate shaped fly-weights or arms 27 are freely pivoted. The outer surfaces of the arms are covered with leather, asbestos or other friction material 28 adapted to engage the inner surface of the housing 22 when the arms 27 are thrown outwardly by the centrifugal force developed by the rotating motor shaft, to lock the motor shaft 13a and container shaft 19 together for united rotation.

A collar 29 provided with cam notches 31 is 100 turnably mounted on the hub of bearing mem- 110

ber 24 and connected with the outer free ends of the arms 27 by links 32. Springs 33, one of which is shown in Fig. 9, are connected respectively to the notched collar 29 and arms 27 to normally draw the arms inwardly and out of engagement with the shell 22.

A second collar 34 having cam projections 35 similar in configuration to the notches 31 of collar 29 and adapted to move into and out of engagement with the same, is slidably fixed to the motor shaft 13a by a key 30. A grooved ring 36, forming part of a ball bearing, is rigidly secured to the collar 34, while the second similar ring 37 of the ball bearing is seated in the collar 38 provided at its outside with opposed studs 39 in engagement with the slotted outer ends of a bifurcated lever 41, pivoted on a pin 43 carried by a bearing 44, fixed on the motor housing.

The lever 41 is connected by a cable 45, which extends over a pulley 46, to a pivotally mounted gear segment 47 in mesh with a rack member 48 pinned to a slide rod 49, normally forced to its lower position (shown in Fig. 2) by a spring 51 mounted thereon between a collar 52 and a rod bearing member 53.

The cover or guard 18 is secured to the casing 16 by a link member 54 whose ends are pivotally connected respectively to the guard and casing, as shown, so as to permit the guard to be limitedly shifted horizontally while closed, and swung into open position as indicated by the dot-and-dash lines in Fig. 2. A projection 55 on link 54 serves as a stop for the guard when in raised or open position. The lower end of link 54 has a flat portion 54a that acts as a stop against casing 16.

A slide plate 56 is movably mounted in a guide slot 57 of a bearing member 58 (see Fig. 7) and connected for movement with the link 54 by projections 58a integral with the plate, which latter extend into grooves 59 in the link. An aperture 61 is provided in the plate 56 for the purpose of permitting the upper reduced end 49a of the rod 49 to pass therethrough when the guard 18 is in properly closed position, as clearly shown in Fig. 1. In this position a latch member 62 on the guard engages with the downwardly turned edge of a flange 16a forming the opening in casing 16, and prevents the guard from being raised or swung open.

It will be noted that in order to open the guard it is necessary to first withdraw the rod end 49a from the aperture 61, then shift the guard rearwardly until the latch member 62 disengages the flange 16a, after which it can be swung open. To assure that such rearward shifting of the guard reaches its maximum extent before it is lifted, segmental lugs 63 are formed on the guard at each side of the link 54 that engage under projections 64 on casing 16 until the proper opening position of the guard has been reached. This is clearly illustrated in Figs. 4, 5 and 6.

Operation

In Fig. 1, the guard 18 is shown locked in closed position, that is, the latch member 62 engages the edge of flange 16a thereby preventing raising of the guard, while rod end 49a extends through aperture 61 in slide plate 56 and prevents the guard from being shifted rearwardly.

If the motor 13 is running when the guard is thus locked, the parts of the centrifugal clutch device 21 will assume the active position illustrated in Figs. 8 and 9 and lock motor shaft 13a and container shaft 19 together for united rota-

tion. The container 12 will consequently be revolved.

The clutch device functions as soon as the flyweights or arms 27 are permitted to fly outwardly and into locking engagement with the shell 22 by the centrifugal action developed by the rotating motor shaft 13a. During such action collar 29 is partly rotated due to its linked connection with the arms, and its notches 31 coat with the cam projections 35 on collar 34 to shift the latter axially and downwardly, thereby shifting collar 38 and moving the rod 49 upwardly through the lever 41 and cable 45, against the action of spring 51.

From this it will be apparent that when the guard 18 is in the position shown in Fig. 1, so that the aperture 61 in plate 56 registers with the rod end 49a, the centrifugal clutch device 21 will function to connect the rotating motor shaft 13a with the container shaft 19 and simultaneously shift the rod end 49a into the aperture 61 to lock the guard in closed position.

Unless the guard is properly closed, that is, unless the plate 56 is in such position that its aperture 61 registers with the rod end 49a, the latter cannot be raised to lock the guard, and consequently the cam parts of collars 38 and 29 will remain in engagement, thereby preventing the turning of the collar 29 so that the arms 37 are prevented from flying outwardly to lock the shell 22.

In other words, when the guard 18 has been properly closed and the motor 13 is running the clutch device 21 will act to simultaneously connect the motor shaft 13a with the container shaft 19 and lock the guard, and unless the guard is properly closed it will not be locked and the shaft 19 will remain disconnected from the motor shaft.

Of course, the safety device shown and described can be changed and modified in various ways without departing from the invention herein disclosed and hereinafter claimed.

I claim:

1. In a centrifugal machine the combination of a casing, a container therein, said container having an opening affording access thereto, a guard for the container, said guard being shiftable in one direction relative to said opening for releasing the same and in another direction for full opening thereof, a container shaft, a drive shaft, a centrifugally operated device for connecting and disconnecting said shafts, and locking mechanism for the guard operatively connected with said device.

2. In a centrifugal machine the combination of a container, a container shaft, a drive shaft, a centrifugally operated device for connecting and disconnecting said shafts, and a shiftable guard for said container adapted to control said device by its shifting action in one plane of movement, said guard including means for swinging movement in another plane, to expose said container.

3. In a centrifugal machine the combination of a container; a guard for the container; a container shaft; a drive shaft; a centrifugally operated device for connecting and disconnecting said shafts comprising a fly-weight and cam member operated thereby; and a locking member for the guard operated by said cam member.

4. In a centrifugal machine the combination of a container; a guard for the container; a container shaft; a drive shaft; a centrifugally operated device for connecting and disconnecting said

- shafts comprising a fly-weight and a movable cam member connected therewith; and means actuated by said guard for controlling the movement of said cam member.
5. In a centrifugal machine the combination of a container, a guard for the container, a container shaft, a drive shaft, an apertured member connected with said guard, a lock member adapted for cooperation with said apertured member, a centrifugally operated device for connecting and disconnecting said shafts, and means connecting said device and lock member. 80
10. In a centrifugal machine the combination of a container, a limitedly shiftable guard for the container, a container shaft, a drive shaft, an apertured plate connected with said guard, a lock rod adapted for cooperation with said apertured member, a centrifugally operated device for connecting and disconnecting said shafts, and means connecting said device and lock rod. 90
15. In a centrifugal machine the combination of a container provided with an opening for affording access to the interior thereof; a cover for closing said opening; means for mounting said cover for shifting movement in the plane of said opening and for swinging movement toward and away from said opening; a container shaft; a drive shaft; a clutch for connecting and disconnecting said shafts, said clutch including a movable member; and locking means for said cover operable by movement of said member to lock or unlock said cover. 95
20. In a centrifugal machine the combination of a container provided with an opening for affording access to the interior thereof; a hinged cover for closing said opening, said cover being mounted on said container so as to enable a sliding movement relative to said opening preliminary to swinging on its hinge for exposing said opening; a container shaft; a drive shaft; a clutch of the centrifugal type for connecting and disconnecting said shafts, and locking means engageable with said cover, said clutch including a centrifugally operated member for actuating said locking means. 100
25. In a centrifugal machine the combination of a rotary container provided with an opening affording access thereto, a cover shiftable in one direction relatively to said opening for releasing the same and in another direction for full opening thereof, a shaft for operating said container; and locking means for said cover operable by said shaft for controlling the shifting of said cover. 105
30. In combination with a casing having an opening, a container mounted in said casing, a shaft for operating said casing, and a cover for closing said container; means for mounting said cover on said casing for shifting movement substantially in the plane of the top thereof to release the same and in another direction to open or close said opening; and locking means operable by said shaft for holding said cover against said shifting movement. 110
35. In a centrifugal machine comprising a casing, and a container drive mechanism mounted therein; a lockable cover mounted on said casing so as to enable a preliminary releasing movement and subsequent opening movement thereof, a cover engaging device movable on said casing to prevent or permit such releasing movement, and means for automatically operating said device by said drive mechanism. 115
40. In a centrifugal machine comprising a casing and a container drive mechanism mounted therein, a lockable cover mounted on said casing so as to be shiftable in a preliminary releasing movement thereof and so as to be pivotable in a subsequent opening movement thereof, a cover locking device movable on said casing to prevent or permit such preliminary shifting or releasing movement of said cover, and means for automatically operating said locking device by said drive mechanism. 120
45. In a centrifugal machine including a casing and a container drive mechanism mounted therein, a cover mounted on said casing so as to enable a preliminary releasing movement laterally and a subsequent swinging opening movement, a locking device on said casing to control said releasing movement, and means for operating said device from said drive mechanism. 125
50. In a centrifugal machine including a casing and a container drive mechanism mounted therein, a cover mounted on said casing so as to permit a preliminary releasing movement in one direction and a subsequent opening movement in another direction, a locking device on said casing to control said releasing movement, means for operating said device from said drive mechanism, and guiding means on said cover to effect cooperation of the cover with said locking device. 130
55. In a centrifugal machine, the combination of a container, a guard for said container, a container shaft, a drive shaft, a clutch for connecting and disconnecting said shafts, said clutch including a housing member fixed to one of said shafts, a complementary member fixed to the other shaft, a centrifugal device connected to one of said members and arranged to engage the other member, a collar freely mounted on said other member and operatively connected to said device, a second collar slidably mounted on said other shaft, said collars including cooperative engageable portions, and means controlled by said guard for operating said clutch. 135
60. In a centrifugal machine, the combination of a container, a guard for said container, a container shaft, a drive shaft, a clutch for connecting and disconnecting said shafts, said clutch including a housing member fixed to one of said shafts, a complementary member fixed to the other shaft, a centrifugal device connected to one of said members and arranged to engage the other member, a collar freely mounted on said other member and operatively connected to said device, a second collar slidably mounted on said other shaft, said collars including cooperative engageable portions, and means controlled by said guard for operating said clutch. 140
65. In a centrifugal machine comprising a casing, and a container drive mechanism mounted therein; a lockable cover mounted on said casing so as to enable a preliminary releasing movement and subsequent opening movement thereof, a cover engaging device movable on said casing to prevent or permit such releasing movement, and means for automatically operating said device by said drive mechanism. 145
70. In a centrifugal machine comprising a casing and a container drive mechanism mounted therein, a lockable cover mounted on said casing so as to be shiftable in a preliminary releasing movement thereof and so as to be pivotable in a subsequent opening movement thereof, a cover locking device movable on said casing to prevent or permit such preliminary shifting or releasing movement of said cover, and means for automatically operating said locking device by said drive mechanism. 150
75. In a centrifugal machine comprising a casing and a container drive mechanism mounted therein, a lockable cover mounted on said casing so as to be shiftable in a preliminary releasing movement thereof and so as to be pivotable in a subsequent opening movement thereof, a cover locking device movable on said casing to prevent or permit such preliminary shifting or releasing movement of said cover, and means for automatically operating said locking device by said drive mechanism.
12. In a centrifugal machine comprising a casing and a container drive mechanism mounted therein, a lockable cover mounted on said casing so as to be shiftable in a preliminary releasing movement thereof and so as to be pivotable in a subsequent opening movement thereof, a cover locking device movable on said casing to prevent or permit such preliminary shifting or releasing movement of said cover, and means for automatically operating said locking device by said drive mechanism.

- tainer shaft, a drive shaft, a clutch for connecting and disconnecting said shafts, said clutch including a housing fixed to said container shaft, a member complementary to said housing fixed 5 to said drive shaft, a plurality of centrifugal arms pivotally connected to said member and arranged to engage said housing, a collar freely mounted on said member and operatively connected to said arms, a second collar slidably mounted on said 10 drive shaft, said collars including cooperative cam portions, and means controlled by said guard for operating said clutch.
19. In a centrifugal machine, the combination of a container, a guard for said container, a container shaft, a drive shaft, a clutch for connecting and disconnecting said shafts, said clutch including a housing fixed to said container shaft, a complementary member fixed to said drive shaft, a plurality of centrifugal arms pivotally 15 connected to said member and arranged to engage said housing, a collar freely mounted on said member and operatively connected to said arms, a second collar slidably mounted on said drive shaft, said collars including cooperative cam portions, and means controlled by said guard for operating said clutch, said clutch operating means including an apertured plate associated with said guard, 20 connected to said member and arranged to engage said housing, a collar freely mounted on said member and operatively connected to said arms, a second collar slidably mounted on said drive shaft, said collars including cooperative cam portions, and means controlled by said guard for operating said clutch, said clutch operating means including a locking plate 25 slidably associated with said guard, a lock rod arranged for registry with said locking plate, means operatively connecting said lock and said second collar, and guiding means to insure registration of said lock rod and plate. 80 85 90 95 100
